UNITED STATES PATENT OFFICE.

CARL F. JOHNSON, OF MILWAUKEE, WISCONSIN.

TIME-CONTROLLED DEVICE.

1,162,171.

Specification of Letters Patent. Patented Nov. 30, 1915.

Application filed March 29, 1915. Serial No. 17,811.

To all whom it may concern:

Be it known that I, CARL F. JOHNSON, a citizen of the United States, residing at Milwaukee, in the county of Milwaukee and 5 State of Wisconsin, have invented certain new and useful Improvements in Time-Controlled Devices, of which the following is a specification.

This invention relates to time controlled 10 devices for actuating valves, switches and the like and is generally applicable where devices of this nature are used.

The invention provides a device having a minimum number of parts all simple and 15 inexpensive to manufacture. It permits ready setting of the time of its periodic actuation, and ready adjustment of the duration of the opening or closing action effected by it. It is applicable to ordinary 20 clock movements and imposes only a slight load on the clock.

Broadly stated the device comprises a lever or other movable element, an interrupted, clock-driven stop, coacting there- 25 with to hold the lever against movement in certain positions of the stop, and a spring to actuate the lever when freed from the stop. The stop conveniently consists of the peripheral portion of a disk which is cut 30 away at the desired point. Near this point on the disk is adjustably mounted a spring. As the disk rotates the end of the lever enters between the disk and spring stressing the latter until the cut-away portion is 35 reached. This frees the lever and the spring shifts it. The continued rotation of the disk causes the spring to clear the lever which then drops back under the action of gravity or a secondary spring. This cycle is per- 40 odically repeated.

The preferred form of the invention, as applied to an admission and exhaust valve, is shown for purposes of illustration in the accompanying drawing, in which:—

45 Figure 1 is a front elevation of an ordinary clock movement with the invention applied. The valve is shown in axial section, and in admission position; Fig. 2 is a similar view showing the device with the valve 50 in exhaust position; Fig. 3 is an enlarged section on the line 3—3 of Fig. 1; Fig. 4 is a perspective view of the actuator arm; and Fig. 5 is an elevation of a control disk 55 adapted to actuate the valve twice in each revolution.

In the drawings 11 represents the frame of an ordinary clock movement the nature of which is familiar to all skilled in the art. This clock movement has the usual minute hand shaft or arbor 12 (see Fig. 3) but in 60 place of the minute hand a disk 13 is frictionally mounted on the arbor 12. It may be turned on this arbor by means of a squared head 14 and such turning is for the purpose of changing the time of actuation 65 of the device. The disk 13 may thus be "set" just as the minute hand of ordinary clocks is "set" without affecting the clock movement.

The disk 13 has a peripheral projecting 70 annular flange 15 which serves as a stop and which is cut away at 16 for a distance dependent on the maximum length of the periodic actuations desired. It is also provided with a tooth or notch 17 with which 75 a pawl 18 coacts to prevent backward or counter clock-wise turning of the disk.

Swiveled on the hub portion of disk 13 and held in any desired angular adjustment 80 thereon by a clamp screw 20 and clamp 21 is 80 an arm 19 provided with a bow spring 22. The bow spring 22 extends diagonally outwardly and rearwardly with reference to the direction of rotation of disk 13 and bears 85 against and projects beyond the stop flange 15 where the latter is cut away at 16.

Mounted on the clock frame 11 is a frame or plate 23 carrying a journal pin 24 and a valve casing 26 having two seats 27 and 28. A valve 29 seats alternately against these 90 two seats and is normally held against seat 28 by a spring 30 coiled around its stem 31. When the valve is against seat 28 the exhaust port around stem 31 is closed and pressure fluid coming through tube 32 is ad- 95 mitted to the controlled device, not shown, through tube 33. When the valve is against seat 27 the supply of pressure fluid is cut off and the controlled device is open to ex- 100 haust.

A lever 34 is mounted on pin 24 and has at one end a lug 35 which normally bears against the inner side of flange 15. The opposite end of lever 34 carries a screw 36 which forms an adjustable thrust member 105 bearing against stem 31 to actuate valve 29. A lug 37 on frame 23 carries a screw 38 which serves as an adjustable stop for lever 34.

In the use of the device the screw stop 38 11v

is so set that the lever 34 may move just far enough to cause lug 35 to clear the inner face of flange 15. The screw 36 is then so set that when valve 29 seats on seat 28 under the action of spring 30, and lever 34 is against screw 38, there is substantially no lost motion between lever 34 and stem 31. This insures the return movement of lever 34 by the action of spring 30 and avoids the necessity of providing any other means for this purpose. In the upright position of the device the weight of lever 34 will assist this action and a little lost motion is thus possible if desired to insure a more certain seating of valve 29 against seat 28.

With the parts in adjustment and the disk 13 turning clockwise, the lug 35 will enter between flange 15 and spring 22 and gradually stress the spring by forcing it inward, as indicated in Fig. 1. This will continue until lug 35 is reached by the cut away portion 16 of flange 15 when the lug 35 will be suddenly forced outward by spring 22, the parts being so proportioned that spring 22 overpowers spring 30. This suddenly shifts valve 29 to seat 27 to cut off the supply of pressure fluid to the controlled device and open this device to exhaust. This condition continues until the end of spring 22 passes lug 35 when spring 30 will restore the parts to their former position. The spring 19 may be angularly adjusted to vary the distance spring 22 projects into the cut away portion 16 and thus vary the time period during which lug 35 is held outward by the spring. The pawl 18 and notch 17 are so placed as to prevent any backward movement which could cause injury to spring 22 through collision with lever 34.

40 The device shown operates the valve at one hour intervals. When shorter intervals are desired a plurality of springs 22 may be used with a disk having a corresponding number of cut away portions as indicated in Fig. 5. In this arrangement the springs 22 are simultaneously adjusted with reference to disk 13. Obviously the disk may, if desired, be driven at a different rotative speed, by any of the means familiar in the art, to 50 secure a similar result.

The device is available to actuate controlling devices generally, such as other types of valve, electric switches, etc., and in fact any light device requiring sudden and precise periodic actuation.

The simplicity of construction and ease of adjustment are important features.

Various other mechanical embodiments of the inventive idea are possible, and I do not limit myself to the precise structure shown except as specified in the claims. For example the forms of the stop and spring are subject to considerable variation without change of function.

65 The device in the form illustrated is de-

signed particularly to control the flushing devices in air washers.

Having thus described my invention, what I claim is:—

1. The combination of a controlling device; a movable actuator therefor; a rotary clock driven member having an interrupted stop adapted periodically to engage said actuator to obstruct its movement from normal position; a spring carried by clock driven member adjacent the interruption in said stop and adapted to engage and be stressed by said actuator by the movement of the clock driven member for shifting said movable member to abnormal position when freed by said stop; and means for restoring said movable member to normal position when freed by said spring. 70 75 80

2. The combination of a controlling device; a movable actuator therefor; a rotary clock driven member having an interrupted stop adapted periodically to engage said actuator to obstruct its movement from normal position; a spring carried by clock driven member adjacent the interruption in said stop and adapted to engage and be stressed by said actuator by the movement of the clock driven member for shifting said movable member to abnormal position when freed by said stop; means for restoring said movable member to normal position when freed by said spring; and means for adjusting said spring relatively to said clock driven member. 85 90 95

3. The combination of a controlling device; a movable actuator therefor; a rotary clock driven member having an interrupted annular stop adapted periodically to engage said actuator to obstruct its movement from normal position; a spring mounted on said clock driven member, extending obliquely into the interruption in said stop and adapted to be engaged and stressed by said actuator as the clock driven member rotates, for shifting said actuator from normal position when freed by said stop; and means for restoring said actuator to normal position when freed by said spring. 100 105 110

4. The combination of a controlling device; a movable actuator therefor; a rotary clock driven member having an interrupted annular stop adapted periodically to engage said actuator to obstruct its movement from normal position; a spring mounted on said clock driven member, extending obliquely into the interruption in said stop and adapted to be engaged and stressed by said actuator as the clock driven member rotates, for shifting said actuator from normal position when freed by said stop; means for adjusting said spring to vary the duration of such shifting; and means for restoring said actuator to normal position when freed by said spring. 115 120 125

5. The combination of a controlling de- 130

vice; a movable actuator therefor; a clock movement; a disk mounted on one of the rotating arbors of said movement, angularly adjustable thereon, and having an interrupted annular flange adapted to engage said actuator to obstruct the movement thereof from its normal position; a bow spring mounted at one end on said disk and having the other end projecting rearwardly through the interruption in said annular flange, and adapted to be engaged and stressed by said actuator as the disk rotates; and means weaker than said spring tending to maintain said actuator in normal position.

6. The combination of a controlling device; a movable actuator therefor; a clock movement; a disk mounted on one of the rotating arbors of said movement, angularly adjustable thereon, and having an interrupted annular flange adapted to engage said actuator to obstruct the movement thereof from its normal position; a bow spring mounted at one end of said disk and having the other end projecting rearwardly through the interruption in said annular flange, and adapted to be engaged and stressed by said actuator as the disk rotates; means for adjusting said spring relatively to said flange; and means weaker than said spring tending to maintain said actuator in normal position.

7. The combination of a shiftable actuator; an interrupted stop for engaging the

actuator to hold the same against shifting; a spring mounted on said stop for engaging said actuator and forcing the same through the interruption in said stop; restoring means for said actuator weaker than said spring; and means for producing relative movement of said actuator and stop to cause the actuator to engage and stress said spring, then move through the interruption in said stop under the action of the spring and then over-travel the spring.

8. The combination of a shiftable actuator; an interrupted stop for engaging the actuator to hold the same against shifting; a spring mounted on said stop for engaging said actuator and forcing the same through the interruption in said stop; means for adjusting the position of said spring relatively to said stop; restoring means for said actuator weaker than said spring; and means for producing relative movement of said actuator and stop to cause the actuator to engage and stress said spring, then move through the interruption in said stop under the action of the spring and then over-travel the spring.

In testimony whereof I have signed my name to this specification in the presence of two subscribing witnesses.

CARL F. JOHNSON.
